FIG. 6

INVENTOR:

WILLIAM R. ENGLAND

BY *George W. Saywell*

ATTORNEY

UNITED STATES PATENT OFFICE.

WILLIAM R. ENGLAND, OF GALION, OHIO.

SHOE-TREE.

Application filed August 13, 1921. Serial No. 491,929.

To all whom it may concern:

Be it known that I, WILLIAM R. ENGLAND, a citizen of the United States, resident of Galion, county of Crawford, and State of Ohio, have invented new and useful Improvements in Shoe-Trees, of which the following is a specification, the principle of the invention being herein explained and the best mode in which I have contemplated applying that principle so as to distinguish it from other inventions.

My invention relates to shoe trees and particularly to that class thereof wherein wooden toe and heel forms are connected by means of an intermediate flexible and elastic steel member. The object of the invention is to produce a shoe tree of the above described character which will be simple and hence economical of construction and which will be capable of efficiently performing its function.

The said invention consists of means hereinafter fully described and particularly set forth in the claims.

In said annexed drawings:

Figure 1 represents a broken plan view of the preferred form of my improved shoe tree;

Figure 2 represents a side elevation of the elements shown in Figure 1;

Figure 3 represents a broken plan view of the intermediate flexible strip;

Figure 4 represents a transverse vertical section, taken in the plane indicated by the line IV—IV, Figure 1;

Figures 5 and 6 represent sections similar to Figure 4, but showing, respectively, slight modifications.

The illustrated embodiment of my invention includes a wooden front or toe form 1 having the usual flat bottom, a wooden rear or heel form 2 and an intermediate connecting thin elastic steel band 3. The two end portions of the band are provided with holes 4.

The said wooden toe and heel members are so formed that the grain of the wood will extend longitudinally when the parts are assembled, by which I mean in a direction substantially parallel with the bottom plane of the shoe to which the form is applied.

In assembling the above described device, the end portions of the steel band are forced

into the toe and heel members longitudinally and hence in a direction parallel with the grain and as is clearly shown in Figs. 4 to 6 inclusive. The direction of the grain and the direction of forcing being as stated, and the band being thin, such entrance of the band into the wood may be readily and quickly effected and a very tight and close union of the parts secured. As shown, the plane of the steel band, when it is in its unflexed position, is made parallel with the flat bottom of the toe member.

After the band has been forced into the toe and heel-members as described, nails 11 are driven downwardly from the top into the respective members and so as to pass through the holes 4 and thus intersects the band. The holes 4 are enlarged as compared with the thickness of the nail so that the latter may be driven without the necessity of exercising extreme care in positioning same so as to pass into said holes.

Should by chance the band and either of the wooden members loosen during use, the nails prevent the withdrawal and separation of the said band and members.

The said nails may be driven from the top or bottom as shown in Figs. 4 and 5, so as to pass into only a portion of the members, or may be driven completely through same as shown in Fig. 6, and clinched or riveted.

What I claim is:

1. In a shoe tree, the combination of a wooden toe and wooden heel form; a flat elastic steel band having its end portions rigidly embedded in said forms respectively, said end portions being each provided with a hole; and a nail driven into each of said forms and passing through said holes respectively.

2. In a shoe tree, the combination of wooden toe and heel forms; a flat elastic steel band having its end portions driven into and rigidly connected with said forms respectively, said end portions being each provided with an enlarged hole; and a nail driven into each of said forms and passing through said enlarged holes respectively.

Signed by me this 27th day of July, 1921.

WILLIAM R. ENGLAND.
